UNITED STATES PATENT OFFICE

ALBERT W. WINSHIP, OF UTICA, NEW YORK

WARDROBE HATBOX

Application filed August 16, 1927. Serial No. 213,410.

This invention relates to a wardrobe hand-carrying case and particularly to a wardrobe hatbox, meaning thereby a hatbox case of about the present size and style of hatboxes but provided with a wardrobe compartment.

The purpose of my invention is to provide a wardrobe hand-carrying case or wardrobe hatbox which is small enough to be readily carried by a woman, but of such construction and arrangement of its parts that a wardrobe compartment is provided.

A further purpose is to provide an article of the class described which is of new and improved construction and well adapted to be used for the purposes intended; and further to provide in such a construction and specially combined therewith a new and improved clothes-rack and mounting therefor, so that the clothes-rack occupies the least possible space when the case or hatbox is closed and still extends the clothes for ready access and inspection when the article of baggage is opened; and further to provide a clothes-rack of the type described wherein the clothes-rod or holder is readily removable from the rack and as readily inserted therein when the clothes-rack is extended; but is held securely in position when the clothes-rack is closed and further to provide in such a clothes-rack a clothes-rod or holder of such construction and so mounted in the clothes-rack that it will minimize any tendency of the clothes to slip from the rack.

Further purposes and advantages of my invention will appear from the specification and claims herein.

Fig. 1 is an isometric view of a wardrobe hand-carrying case known as a hatbox embodying my invention with the cover opened and with the clothes rack in extended position.

Fig. 2 is a vertical sectional view through the said wardrobe hatbox closed.

Fig. 3 is a horizontal sectional view of the parts immediately below line 3—3 of Fig. 1.

Fig. 4 is an enlarged vertical sectional view of the clothes-rack and adjacent part of the cover as seen on line 4—4 of Fig. 3.

Fig. 5 is a right hand side elevation of the right hand bracket of the clothes rack when

it is in raised position with the adjacent part of the cover shown in section.

Fig. 6 is a front elevation of a modified form of my invention with the case opened and Fig. 7 is a vertical sectional view of 55 such case closed.

Referring to Figs. 1—5 of the drawings in a more particular description, it will be seen that my wardrobe case or hatbox consists of a box-like case 8 and a cover 9 hinged thereto, it being understood that said parts are of a construction suitable for articles of portable baggage. It will be understood further that the combining of a wardrobe section into or with a hatbox is done in such manner as not to greatly reduce the amount of space in the box available for hats and other articles of clothing in trays or compartments, and that the wardrobe compartment is made L-shaped in outline when the 70 box is closed, so as to make the effective length of the wardrobe compartment long enough to support ladies' dressed or men's clothes when once folded and yet to not increase the size of the hatbox. 75

Referring first to Figs. 1 to 5. The main case 8 consists of a bottom 10, relatively narrow front 11, a back 12 higher than the front 11 and opposite slanting sides 13—13, extending from the front to the back. The 80 front 11 and the back 12 are so termed as that will be the relative position of those parts when the hatbox is open as it is seen in Fig. 1. To the upper edge of the back 12 is hinged the shallow flange 51 of the cover 85 9. The upper end of the cover as the parts are seen in Fig. 1 has a front or top flange 14, as much higher than the flange 51, as the back 12 is higher than the front 11 of the main case. These two unequal flanges 51 90 and 14 of the cover are connected by slanting flanges 15—15. When the cover 9 is closed down upon the case a rectangular box in vertical section is obtained as appears from Fig. 2. Ordinarily when the hatbox is thus 95 closed, it will be stood up as appears in Fig. 2 with the back 12 of the case serving as the bottom of the whole article. The front of the case is provided with a handle 16 and suitable catches 17 are provided with their 100

co-operating parts upon the front 11 and the side flange 14 respectively.

Spaced from the back 12, the main case 8 is provided with a partition 18 extending the width of the case and extending from the bottom 10 upwardly about to a line level with the front 11. This partition forms a chamber or well 19 at the back of the case into which hang the lower portions of dresses or other garments 20 folded over the clothes-rod or holder 21 which in turn is mounted in the clothes-rack generally denoted by the numeral 22, secured to the upper part of the cover 9 as seen in Fig. 1.

Preferably a removable partition 23 extends from the fixed partition 18 to the front 11 to aid in holding in place a removable tray 24 on one side of said partition 23. A hat or hats may be placed in the chamber to the left side of the removable partition 23 and other articles of clothing may be placed in the chamber to the right of said partition, below the tray 24. If desired the tray 24 and also the removable partition 23 may be removed in order that this part of the case may house one or more very large hats.

The clothes-rack 22 is composed of opposite metallic sides 25 and 26 at the left and right respectively connected by a wooden strip 27. In the free ends of this clothes rack there is normally supported the opposite ends of the clothes-rod or holder 21. Preferably metallic plates 28—28 are placed on the inner surface of the slanting cover flanges 15 slightly down from the top 14 of the cover. To each one of these plates there is pivotally secured as by pivot 29 the opposite sides or brackets 25 and 26 of the clothes rack.

Fig. 4 shows a plan or side view of the left hand plate 28 and the bracket 25 secured thereto. At the upper part of the bracket 25 as seen in Fig. 4, said bracket is provided with an ear 30 projecting laterally to afford means of readily fastening the brace 27 to the bracket as by rivets 31. Near the outer end of the side or bracket 25 of the clothes-rack 22 there is provided an angular, preferably squared, hole 32 adapted to receive the correspondingly shaped end of the clothes-rod or holder 21 and keep said rod 21 from rotation. The right hand side or bracket 26 of the clothes-rack is similar to the bracket 25 in construction and pivotally mounted, except that as appears from Fig. 5 said bracket 26 is provided near its outer end with an elongated slot 33 having an opening 34 therewith at its upper side. The rod 21 is removably mounted in the clothes-rack 22 by inserting the squared left hand end of said rod longitudinally into the square hole 32 in side or bracket 25 of the rack whereupon the squared end of the right hand end of the rod will be passed downwardly through the opening 34 into the elongated slot 33 of the

right hand bracket 26. The wooden strip 27 being rigidly secured to the ear 30 of bracket 25 and to similar ear 30^a on bracket 26 holds the two brackets 25 and 26 to swinging movement in unison and further braces 70 the said brackets. Inturned ears 35 on the lower end of the plates 28 stop the downward movement of the clothes-rack at open position as shown in Figs. 1 and 4. The clothes-rack may be swung to upward and housed position as shown in Fig. 2 by swinging said rack upwardly on its pivotal connections. Releasable spring locking means are provided to aid in holding the clothes-rack in such upward position. Such means may consist of an inwardly extending boss 36 upon each plate 28 so placed as to engage a hole or depression 37 in the sides or brackets 25 and 26 when the clothes-rack is raised to housed position. The said brackets will yield enough to allow the outer surface of said brackets to ride past the boss 36 until the hole or depression 37 comes into register with said boss. In a similar obvious manner this spring latch mechanism may be disengaged by pulling the clothes-rack downwardly.

A block 38 is provided in the cover near its upper right hand corner so as to bear against the rod 21 near the bracket 26, when the clothes-rack is in raised position. This block 95 accordingly prevents this end of the rod 21 from leaving the elongated slot 33 when the clothes-rack is raised.

Ladies' dresses or men's clothes may be placed one or more at a time in position 100 over the clothes-rod 21 when the clothes-rack 22 is in lowered position. The size and proportion of the parts of this wardrobe hatbox is such that an ordinary dress will hang free over said rod making a single 105 fold of the clothes at their center and with the opposite ends of the clothes hanging freely into the well 19. Another convenient way of loading the rod 21 is to place the desired number of dresses or other garments 110 one on top of another in extended or flat position and then pass the clothes-rod 21 underneath the center of the pile of dresses. By raising the rod 21 the whole pile of 115 clothes will fall to folded position on the opposite sides of said rod and may then be bodily placed in the wardrobe compartment as already described with reference to the separate rod 21. When the desired number of garments have been placed over the 120 rod 21 the clothes-rack will be swung up to upward position and the clothes 20 will be confined more or less by upper and lower tie straps 39 and 40 preferably elastic and conveniently provided with detachable hook fasteners. The wardrobe hatbox is then 125 ready for its final closing motion of bringing the cover down upon the case, or what is the same of bringing the case up to the cover so that the parts come to the closed 130

position as shown in Fig. 2 with the clothes coming to the L-shaped form as clearly shown in Fig. 2, the bend being formed opposite the lower tie strap 40. The lower 5 ends of the clothes are still in the well but now in a horizontal position but with the greater part of the clothes hanging freely downwardly in a vertical position. The partition 18 prevents the contents of the 10 other part of the body of the case from pressing against the clothes in the well therebeneath.

By having the clothes rack swing upwardly to closed position, the full height 15 of the raised cover and the full depth of the well 19 can be utilized for hanging the clothes straight down on the clothes rod 21 without such clothes touching the bottom of the well after the rack 22 is raised and 20 whether the hatbox is closed or open. The several inches of straight hanging space gained by this construction enables the wardrobe compartment in the hat box to be large enough for full sized clothes.

25 Preferably the clothes rod 21 is covered with felt or velveteen 41 which overcomes any tendency of the clothes to slide either way off from the rod.

25 Figs. 6 and 7 show a modified form of my invention in that the hat box is made of a circular case 42 and a circular cover 43 both flattened as is usual with round hat boxes to form a suitable base and also the hinging line. The case 43 slants up towards its rear 35 edge where the cover is hinged thereto and the flattened portion 44 of the flange of the cover is narrower than the rest of the flange of said cover as appears from Figs. 6 and 7. In this form of my invention the clothes rod 45 is not mounted in a swinging clothes rack but is removably mounted in left and right hand brackets 46 and 47. The bracket 46 is rigid and is rigidly 40 mounted on the upper part of the flange of the cover and is provided with a square hole to receive by endwise movement of the rod 45 the left hand squared end of the rod. The right hand bracket 47 has one end fastened to the flange of the cover 43 but has 45 its other and lower end resilient so as to be temporarily pressed back towards the flange of the cover to allow this squared end of the rod to enter a square hole in the resilient end of the bracket. When the bracket is 50 allowed to spring back to its normal position it holds the rod 45 securely.

55 In this form of hat box the well 48 in the case is formed not by a solid partition but simply by a transverse rod 49 defining the top of the well.

60 It will be understood that every inch added to the effective height of the clothes supporting rod above the bottom of the well during packing as well as during the 65 closed position adds two inches to the

length of clothes that can be carried by the case due to the clothes being folded once over the clothes supporting rod.

70 Preferably I form the body and cover of the case so that the case is, as it were, divided or cut on the bias with the shallow side or back flange 51 of the cover hinged to the back high wall 12 of the body as the parts are seen in Figs. 1 to 5 or with the corresponding narrow flange 44 of the cover 75 hinged to the back high wall of the case 42 as the parts are seen in Figs. 6 and 7. This construction, characterized by the consequent slanting sides of the body and the slanting side flanges of the cover, was made 80 for several reasons and is of more importance than at first appears in obtaining co-operation of the parts and in order to obtain certain advantages and avoid certain disadvantages.

85 The height and thickness of a hand-carrying case are very definitely fixed if the case is to be practicable to carry and every inch of the height and thickness of a case of such practicable size must be utilized to 90 carry dresses wardrobe style, that is, hung up, even when folded over once intermediate their length and given one other bend to go into the well of the case.

95 At the top of the cover the flange should be deep enough to hold the doubled layers of the dresses near the clothes supporting cross bar 21 but at the bottom of the cover it is better to reduce the width of the flange very considerably. The depth thus taken 100 off of the cover is added to the depth or height of the well in the body of the case and so when the case is in opened position gives greater clear height for the dresses to hang straight down into the well from 105 the rod either in its lowered or its raised position.

110 For clothes of a length approaching the capacity of the case the clothes will touch the bottom of the well when the rod (assuming it to be of the movable type as suggested in Figs. 1-5) is in its lowered or loading position, but when the rod is raised to its real carrying position the bottom ends of these clothes are lifted just clear of the bottom of the well by reason of the two or two and a half inches more or less gained in the well by the narrow flange at the bottom of the cover.

115 Furthermore, by reason of the narrow flange at the bottom of the cover the clothes even when raised and moved back towards the main flat face of the cover will still hang down in a substantially straight line into the well and do not have to make a 120 decided turn out from the flat main face of the cover past a deep flange.

125 Even when the lower tie strap is placed across the clothes and hooked into place to hold the clothes back against the cover, the 130

flange at the bottom of the cover is so narrow that no appreciable bend is imparted to the clothes.

The narrow flange at the bottom of the 5 cover and the consequent height added to the well allows as much height during packing and unpacking as is gotten in the carrying position and this effective height during packing and unpacking is fully as necessary 10 as sufficient height or extent when the case is closed.

Another advantage gained by the narrow flange towards the bottom of the cover is that the user has a better opportunity to 15 arrange the edges of the clothes neatly preparatory to strapping them back into position because she can both clearly see and easily reach the edges of the clothes opposite the narrow flange which would not be the case 20 were the flange two or three inches deep.

The narrow flange at the bottom of the cover as distinguished from a deep flange allows the clothes to hang down from the elevated rod close to a substantial level or 25 uninterrupted flat packing surface, the upper two-thirds or so being the flat main inner surface of the cover and the lower one-third being the back or high side of the well. A deep flange at the bottom of the cover 30 would create a step in this packing surface and make an extra angle in the clothes when arranged in the case. The width of this narrow bottom flange as I show it is not enough to interfere with the aforesaid flat 35 packing surface desired.

The presence of the flange though narrow serves mechanically to strengthen the bottom edge of the cover, allows better hinge construction and also admits of the outside 40 of that edge of the cover being given the rounded corner effect that is now generally desired on such cases.

While I have thus pointed out the advantages that make the slanting side the most 45 practical and the preferred form, it will be understood that my invention is not limited in its application to a case so cut on the bias but that as shown in several of the claims my invention broadly can be applied 50 to a hand-carrying case without regard to whether the cover and body are cut on the bias.

What I claim as new and desire to secure by Letters Patent is:

55 1. In a wardrobe suitcase, or the like the combination of a box-like case slanting to be higher at one side than at the opposite side and provided with a partition spaced from the back higher side of the case and 60 forming a well, a flanged cover hinged to the free edge of the high side of the case and having its flanges reversely slanted relative to the sides of the case to form a rectangular box, a clothes rack having its inner ends 65 pivotally mounted within the upper corners

of the cover and adapted to be swung therewithin or extended downwardly without the cover over the well and a clothes rod connecting the free ends of the clothes rack.

2. In a wardrobe suitcase, or the like the 70 combination of a box-like case slanting to be higher at one side than at the opposite side and provided with a partition spaced from the back higher side of the case and forming a well, a flanged cover hinged to 75 the free edge of the high side of the case and having its flanges reversely slanted relative to the sides of the case to form a rectangular box, a clothes rack having its inner ends pivotally mounted within the upper 80 corners of the cover and adapted to be swung therewithin or extended downwardly without the cover over the well and a removable clothes rod connecting the free ends of the clothes rack.

3. In a wardrobe suitcase, or the like the 85 combination of a box-like case slanting to be higher at one side than at the opposite side and provided with a partition spaced from the back higher side of the case and forming a well, a flanged cover hinged to 90 the free edge of the high side of the case and having its flanges reversely slanted relative to the sides of the case to form a rectangular box, a clothes rack having its inner ends pivotally mounted within the upper corners of the cover and adapted to be swung therewithin or extended downwardly without the cover over the well and a non-rotatable clothes rod connecting the free ends 95 of the clothes rack.

4. In a hand-carrying case, the combination of a box-like body, a cover hinged thereto, a partition in the body forming a well in the body beneath the raised cover and at 105 a right angle to the cover when the case is closed, a clothes rack movably mounted near the free end of the cover and having a transversely extending clothes rod supported in said rack, said rack being adapted to be 110 moved so as to hold said rod farther from said cover for folding the clothes thereover with their ends extending down into said well and said rack being adapted to be moved back to carry said rod nearer the 115 cover and means for holding the clothes opposite the cover towards the said cover.

5. In a hand-carrying case, the combination of a box-like body, a cover hinged thereto, a partition in the body forming a well 120 in the body beneath the raised cover and at a right angle to the cover when the case is closed, a transversely extending clothes-supporting rod extendably mounted in the free end of the cover whereby the rod when 125 moved away from the cover may have full length dresses folded thereover with their depending ends extending down into the well and whereby the rod and the clothes thereon may be moved closer towards the 130

cover, and means for holding the clothes opposite the cover towards said cover.

6. In a wardrobe suitcase, or the like, the combination of a box-like case slanting to be higher at one side than at the opposite side and provided with a partition spaced from the back higher side of the case and forming a well on one side and a space for wearing apparel on the other side, a flanged cover hinged to the free edge of the high side of the case and having its flanges reversely slanted relative to the sides of the case to form a rectangular box, and transverse supporting means adapted to have a garment folded thereover, whereby the lower end of the garment may be received in the well, said supporting means being removably and replaceably mounted in the upper end of the cover.

20 In witness whereof I have affixed my signature, this 27th day of July, 1927.

ALBERT W. WINSHIP.

DISCLAIMER

1,728,223.—*Albert W. Winship, Utica, N. Y. WARDROBE HATBOX. Patent dated September 17, 1929. Disclaimer filed May 4, 1932, by the patentee.*

Hereby enters this disclaimer to that part of the claims in said specification which is in the following words, to-wit:

“4. In a hand-carrying case, the combination of a box-like body, a cover hinged thereto, a partition in the body forming a well in the body beneath the raised cover and at a right angle to the cover when the case is closed, a clothes rack movably mounted near the free end of the cover and having a transversely extending clothes rod supported in said rack, said rack being adapted to be moved so as to hold said rod farther from said cover for folding the clothes thereover with their ends extending down into said well and said rack being adapted to be moved back to carry said rod nearer the cover and means for holding the clothes opposite the cover towards the said cover.

“5. In a hand-carrying case, the combination of a box-like body, a cover hinged thereto, a partition in the body forming a well in the body beneath the raised cover and at a right angle to the cover when the case is closed, a transversely extending clothes-supporting rod extendably mounted in the free end of the cover whereby the rod when moved away from the cover may have full length dresses folded thereover with their depending ends extending down into the well and whereby the rod and the clothes thereon may be moved closer towards the cover, and means for holding the clothes opposite the cover towards said cover.

“6. In a wardrobe suitcase, or the like the combination of a box-like case slanting, to be higher at one side than at the opposite side and provided with a partition spaced from the back higher side of the case and forming a well on one side and a space for wearing apparel on the other side, a flanged cover hinged to the free edge of the high side of the case and having its flanges reversely slanted relative to the sides of the case to form a rectangular box, and transverse supporting means adapted to have a garment folded thereover, whereby the lower end of the garment may be received in the well, said supporting means being removably and replaceably mounted in the upper end of the cover.”
